UNITED STATES PATENT OFFICE.

MARTIN ARMSTRONG, OF KENNEY, TEXAS.

TELEGRAPH INSTRUMENT.

SPECIFICATION forming part of Letters Patent No. 730,858, dated June 16, 1903.

Application filed February 28, 1902. Serial No. 96,181. (No model.)

To all whom it may concern:

Be it known that I, MARTIN ARMSTRONG, a citizen of the United States, residing at Kenney, in the county of Austin, State of Texas, have invented certain new and useful Improvements in Telegraph Instruments; and I do hereby declare the following to be a full, clear, and exact description of the invention, such as will enable others skilled in the art to 10 which it appertains to make and use the same.

Generally stated, the object of my invention is to provide a simplified and improved form of telegraph-transmitter whereby any person may send a telegraphic message even 15 though such person may have no knowledge of the Morse alphabet.

A special object is to provide a construction whereby the transmitter may be easily and cheaply manufactured.

Another object is to provide a construction which will facilitate the operation of the transmitter.

It is also an object to provide certain details and features of improvement tending to 25 increase the general efficiency and serviceability of a telegraph-transmitter of this particular character.

To the foregoing and other useful ends my invention consists in matters hereinafter set 30 forth and claimed.

In the accompanying drawings, Figure 1 is a plan of my improved telegraph-transmitter and also of an ordinary receiving instrument or sounder, together with the stylus which 35 forms a part of the transmitting instrument, the electrical connections between the three instrumentalities being shown in diagram. Fig. 2 is a cross-section of a transmitting-board on line 2 2 in Fig. 1.

The receiving instrument or sounder 5 can be of any suitable known or approved character. The battery 6 can also be of any suitable character.

The transmitter-board A preferably has its 45 upper surface provided with a number of transverse grooves 12, which are provided with widened portions 15 at their starting-points. As will be observed, a letter of the alphabet or a numeral is arranged opposite 50 the starting-point of each groove. The metal 10 is preferably run into recesses formed in the top of the board, these recesses being so

formed that when filled with metal each groove is provided with one or more contacts corresponding to the letter or numeral allotted 55 to such groove. Preferably the recesses for the metal are formed, the metal is run in, and the grooves 12 are then cut through the flush surfaces of the insulation 9 and the metal 10. The contacts thus provided for the guide-grooves 12 can all be electrically connected 60 in any suitable manner. For example, a metal back plate X can be provided for the board, and the metal run into the recesses can make contact with this plate. It is obvious, however, that any other expedient can be adopted for assuring a perfect electrical connection between all of the contacts of the different grooves. The stylus B can have an insulating portion 8, provided with a metal 65 contact-point b. When the sounder, the battery, the stylus, and the metal 10 of the board are all connected up in series, as shown in Fig. 1, a message can be transmitted over the line from the board to the sounder by simply 70 drawing the contact-point of the stylus over the contacts in the different grooves—that is to say, such a message can be transmitted by drawing the stylus along the grooves corresponding to the letters which spell out the 75 words of the message. If desired, longitudinal guide-grooves a can be formed in the top of the board, and the contacts of these grooves can be provided by the metal 16, which is run into recesses in a manner similar to that already described. The contacts thus provided for the guide-grooves a can be of a character to spell out either words or sentences. Consequently in this case each guide-groove may represent a word or sentence. 80 Thus the board can be provided with a number of grooves any one of which represents a word or sentence and also with a number of grooves any one of which represents a letter or numeral. The metal for the grooves 85 a can be electrically connected with the circuit in the manner previously described. Thus it will be seen that I provide an exceedingly simple and inexpensive form of telegraph-transmitter which can be operated 90 by persons having no knowledge of the Morse code as well as those skilled in the art of sending telegraphic messages in the ordinary manner.

With my improved transmitter any person can readily learn the Morse alphabet and can in a short time become proficient in sending telegraphic messages in the ordinary manner. In other words, my invention may be employed for teaching the art of sending telegraphic messages with an ordinary key.

What I claim as my invention is—

1. The combination of a telegraph-transmitter consisting of a support composed of insulation, recesses formed in the top of said support, suitable metal run into said recesses, parallel grooves cut through the flush surfaces of the said insulation and metal, numerals and letters of the alphabet being arranged in their proper order at the starting-points of said grooves, the said metal being so disposed as to provide each groove with one or more contacts corresponding to the letter or numeral allotted to such groove, a stylus adapted to be drawn along the said grooves and over the contacts, a telegraph-receiver, a suitable source of current, suitable conductors for connecting the stylus and metal of the transmitter with said receiver and source of current, means for electrically connecting all of said contacts, whereby the passage of said stylus over the contacts in any particular groove will cause said receiver to sound the letter or numeral allotted to such groove.

2. The combination of a telegraph receiving instrument, a suitable source of current, a telegraph transmitting instrument, said transmitting instrument consisting of a board of insulation provided with recesses, metal run into said recesses, parallel grooves cut in the flush upper surfaces of said board and metal, suitable characters or indicating devices located opposite the starting-points of said grooves, the said metal being so disposed as to provide each groove with one or more contacts corresponding to the character or indicating device allotted to such groove, a

stylus adapted to be drawn along said grooves 45 and over said contacts, means for electrically connecting all of said contacts, and suitable conductors for connecting the said stylus and the metal of said transmitting instrument with said receiving instrument and source of 50 current.

3. A telegraph instrument comprising a board of insulation provided with recesses, metal run into said recesses, parallel grooves cut in the flush surfaces of said metal and insulation, said grooves being widened at their starting-points, letters of the alphabet arranged opposite said widened portions of the grooves, said metal being so distributed as to provide each groove with one or more 60 contacts corresponding with the letter allotted to such groove, and a stylus adapted to be drawn along said grooves, means for electrically connecting all of said contacts.

4. A telegraph transmitting instrument 65 comprising a board of insulation provided with recesses, metal run into said recesses, a set of parallel grooves cut in the flush surfaces of said metal and insulation, numerals and letters of the alphabet arranged opposite 70 the starting-points of said grooves, said metal being so distributed as to provide each groove with one or more contacts corresponding to the letter or numeral allotted to such groove, said board having another set of parallel 75 grooves extending at right angles to said first-mentioned set of grooves, each of said last-mentioned grooves being provided with contacts corresponding to a word or sentence, means for electrically connecting all of said 80 contacts, and a stylus adapted to be drawn along said grooves.

In testimony whereof I affix my signature in presence of two witnesses.

MARTIN ARMSTRONG.
